180,100

INCINERATOR

Zinon C. Possis, Minneapolis, Melvin J. Straub, Hopkins, and William C. Berg, Minneapolis, Minn., assignors to Pioneer Specialties, Inc., Minneapolis, Minn., a corporation of Minnesota

Application March 31, 1955, Serial No. 35,306

Term of patent 14 years

(Cl. D81—1)

The figure is a front perspective view of an incinerator embodying our new design. The back and side not shown, are substantially like the respective front and side shown.

We claim:

The ornamental design for an incinerator, as shown and described.

References Cited in the file of this patent

UNITED STATES PATENTS

D. 106,018	Copeman	Sept. 14, 1937
D. 134,814	Hoskins	Jan. 19, 1943
1,891,069	Suciu	Dec. 13, 1932

OTHER REFERENCES

House Beautiful, June 1950, page 72, Alsto Co. trash disposal unit.